Specification for Design.

Patented Oct. 8, 1918.

Application filed April 29, 1916. Serial No. 94,506. Term of patent 3½ years.

To all whom it may concern:

Be it known that I, CHARLES H. LAING, a citizen of the United States, residing at Racine, in the county of Racine and State of Wisconsin, have invented a new, original and ornamental Design for Clothes-Trays, of which the following is a specification, reference being had to the accompanying drawing, forming part thereof.

Figure 1 is a perspective view of a clothes

tray showing the design of this invention; and,

Fig. 2 is a front view thereof.

I claim the ornamental design for a clothes tray as shown.

CHARLES H. LAING.
